UNITED STATES PATENT OFFICE.

ALFRED F. HARRIS, OF WARREN, OHIO, ASSIGNOR TO THE HARRIS AUTOMATIC PRESS COMPANY, OF NILES, OHIO, A CORPORATION OF OHIO.

FEEDING MECHANISM FOR PRINTING-PRESSES.

No. 844,935.

Specification of Letters Patent.

Patented Feb. 18, 1907.

Application filed June 12, 1905. Serial No. 264,835.

To all whom it may concern:

Be it known that I, ALFRED F. HARRIS, of Warren, in the county of Trumbull and State of Ohio, have invented certain new and useful Improvements in Feeding Mechanism for Printing-Presses; and I do hereby declare the following to be a full, clear, and exact description of the invention, such as will enable others skilled in the art to which it applies to make and use the same.

The primary object of this invention is to provide improved means for insuring perfect register of stock, not only relatively to the grippers, but also as to the type; the latter being of primary importance in multicolor-work.

A further object is to remove all bends or crimps in the paper and flatten it out against the impression-cylinder.

The invention will be hereinafter fully set forth, and particularly pointed out in the claims.

In the accompanying drawings, Figure 1 is a view in side elevation, showing but a portion of a printing-press. Fig. 2 is a view in perspective with parts broken away.

Heretofore difficulty has been experienced in multicolor-work or any printing requiring that the stock be passed through the press more than once when such stock is not perfectly smooth throughout its entire length. Should the stock be bent or curled, especially at its forward edge, perfect register with the grippers cannot always be secured, and if the stock is so bent or curled when first engaged by the grippers it may be flattened out in its first passage through the press, but not until after the first imprint has been made, and hence in going through the press the second time the stock will be thrown out of register. In other words, when first printed upon the distance on a short line between the ends of the sheet being less than when the latter is passed through the press the second time imperfect register will result.

Now by means of my invention the front edge of each sheet is flattened out as soon as it is brought up to the impression-cylinder in position to be engaged by the grippers, and it is also flattened throughout its length as it passes onto such cylinder. This I accomplish by means of a continuous blast of air against the front end of the stock, and throughout

the length thereof, such blast being at right angles to the line of travel to the impression-cylinder. This blast holds the front edge of each sheet of stock tight against the cylinder and flattens it throughout its length as it is taken up and passes around the latter. By a "continuous" blast of air I mean one that is continuous from the time the front end of the sheet comes thereunder and until the rear end is in line therewith. Preferably the air is supplied from a discharge-pipe located in close relation to and parallel with the impression-cylinder, such pipe being perforated on its lower face and having a supply-pipe opening thereinto at its center, with the result that the strongest blast is through the perforations nearest the middle of the discharge-pipe.

Referring to the drawings, 1 designates the impression-cylinder of a printing-press, 2 the grippers thereon, and 3 the type-carrying cylinder, all of which may be of any preferred construction.

4 designates the air-discharge pipe mounted at its ends in holders 5, supported by a tie-rod 6. This pipe 4 is located in parallelism to the impression-cylinder, with sufficient space intervening to allow the stock to pass freely to the cylinder, such stock being fed by any suitable means. In the lower under face of this pipe are holes or perforations 7, through which the air is discharged, and into the center of such pipe opens the supply-pipe 8, leading from any suitable blower or compressor. (Not shown.) The blasts are strongest at the center of the discharge-pipe, being of gradually-lessened intensity toward the ends thereof. This blast being continuous throughout the length of each sheet, the forward edge of the latter as it is brought into place to be engaged by the grippers is flattened against the impression-cylinder, thus removing any bend or curve therein. As the sheet is taken up by the grippers and carried around the cylinder it is flattened against the latter throughout its entire length, so that no matter how many times it may be passed through the press proper register with the type will be secured.

The advantages of my invention will be apparent to those skilled in the art. It will be especially observed that by means thereof I am enabled to flatten out the forward edge of each sheet of stock no matter how bent or

crumpled it may be and that in consequence I obtain perfect register, which is of such great importance in multicolor-work. Furthermore, my invention renders unnecessary the use of brushes or other means riding on the impression-cylinder in close relation to the point of impression.

I claim as my invention—

1. The combination with a printing-press having an impression-cylinder, and grippers on the latter, of means for supplying a blast of air against the front end of each piece of stock as it is brought into position to be engaged by said grippers.
2. The combination with a printing-press having an impression-cylinder, and grippers

on the latter, of a pipe paralleling said cylinder and arranged in juxtaposition to the point at which the stock is engaged by said grippers, said pipe having openings in its lower face, and means for supplying a blast of air through said pipe against the front end of the stock as it is brought into position to be engaged by said grippers.

In testimony whereof I have signed this specification in the presence of two subscribing witnesses.

ALFRED F. HARRIS.
